UNITED STATES PATENT OFFICE

167,164

CHILD'S BOOT

John B. Reinhart, Jr., and Joseph B. Ruebel,
Farmington, Mo., assignors to Trimfoot Company, Farmington, Mo.

Application April 17, 1952, Serial No. 19,358

Term of patent 14 years

(Cl. D7—7)

To all whom it may concern:

Be it known that we, John B. Reinhart, Jr. and Joseph B. Ruebel, citizens of the United States, residing at Farmington, Missouri, have invented a new, original, and ornamental Design for a Child's Boot, of which the following is a specification, reference being had to the accompanying drawings, forming part hereof.

We claim:

The ornamental design for a child's boot, substantially as shown.

JOHN B. REINHART, JR.
JOSEPH B. RUEBEL.
